UNITED STATES PATENT OFFICE.

MORRIS LEVITAN, OF NEW YORK, N. Y.

DESIGN FOR AN ARM FOR ELECTRIC-LIGHTING FIXTURES.

Application filed August 12, 1926. Serial No. 18,699. Term of patent 3½ years.

To all whom it may concern:

Be it known that I, MORRIS LEVITAN, a citizen of the United States, residing at No. 868 Faile Street, borough of Bronx, city and State of New York, have invented a new, original, and ornamental Design for an Arm for Electric-Lighting Fixtures, of which the following is a specificatin, reference being had to the accompanying drawing, forming a part thereof.

The figure shows a perspective view of my new, original, and ornamental design for an arm for electric-lighting fixtures.

I claim:

The ornamental design for an arm for electric-lighting fixtures, as shown.

MORRIS LEVITAN.
